J. ELNIFF.

VESSEL PROPELLING APPARATUS.

APPLICATION FILED DEC. 18, 1907.

917,935.

Patented Apr. 13, 1909.

UNITED STATES PATENT OFFICE.

JOHN ELNIEF, OF KANSAS CITY, MISSOURI.

VESSEL-PROPELLING APPARATUS.

No. 917,935.

Specification of Letters Patent.

Patented April 13, 1906.

Application filed December 18, 1907. Serial No. 407,077.

To all whom it may concern:

Be it known that I, JOHN ELNIEF, a citizen of the United States, residing at Kansas City, in the county of Jackson and State of Missouri, have invented certain new and useful Improvements in Vessel-Propelling Apparatus, of which the following is a specification.

This invention relates to vessel propelling apparatus and more especially to apparatus for propelling a vessel by compressing air and discharging the same through ports against and into the water sustaining the vessel.

A further object is to produce apparatus of the character named whereby the vessel may be propelled forwardly, rearwardly, laterally to one side or the other or may be turned quickly on a short radius toward either side.

A still further object is to produce means enabling a single operator to easily and reliably control the movement of the vessel.

With these general objects in view and others as hereinafter appear, the invention consists in certain novel and peculiar features of construction and organization as hereinafter described and claimed; and in order that it may be fully understood reference is to be had to the accompanying drawing, in which—

Figure 1, is a side elevation of a vessel equipped with propelling and steering apparatus embodying my invention. Fig. 2, is a vertical longitudinal section taken substantially in the center of the vessel. Fig. 3, is a top view of the vessel with the upper deck broken away to disclose underlying features of construction. Fig. 4, is a vertical transverse section taken on the line IV—IV of Fig. 3. Fig. 5, is an enlarged section taken on the line V—V of Fig. 1. Fig. 6, is an enlarged perspective view of the air holder.

In the said drawing, 1 indicates a boat of any type, provided below the water level with a large number of port holes 2, the series of holes extending substantially from the front to the rear end of the vessel, which preferably is not provided with a rudder.

3 and 4 indicate nozzles secured externally to the hull of the vessel and arranged to discharge rearwardly and forwardly respectively, the former extending from the rear end of the vessel to about the point where the latter begins to taper sharply toward the prow. The nozzles 4 are arranged forward of the series of nozzles 3 and are provided with spring-plate extensions or valves 5 which un-

der their resiliency and the pressure or resistance of the water as the vessel moves forward are normally closed to prevent water entering the nozzles and the communicating ports 2. 60

An engine or its equivalent, not shown, is arranged in the vessel for the purpose of operating the piston of the cylinder 6, the piston stem 7 projecting into a pump or air compressor 8 of the usual or any preferred type, 65 it being understood that by preference the mechanism described will be duplicated and capable of independent operation so that in the event that one engine is incapacitated the other may be utilized.

9, indicates pipes leading from the air pumps or compressors 8 and equipped with independent controlling valves 10.

11 indicates a large compressed-air holder to receive the air from pipes 9, said holder 75 being preferably located above the plane of the water level.

12 indicates discharge pipes extending from the valve-boxes 12^a communicating with the upper end of the holder toward the 80 contiguous sides of the vessel and 13 are longitudinal distributing pipes communicating with pipes 12 and preferably supported upon a deck 14 of the vessel or in any other suitable or preferred manner. 85

15 are discharge pipes leading downward from pipes 13, and equipped with numerous small branch pipes or ports 16 communicating with the ports 2 having the nozzles 3, so that all of the air discharged through pipes 90 12 shall eventually escape from nozzles 3 and consequently rearwardly.

17 are pipes projecting laterally from the holder like pipes 12 and communicating with the front ends of distributing pipes 18 95 in the bow of the vessel and by preference supported upon deck 14 of the latter.

19 are pipes extending downwardly from pipes 18 and provided with numerous small branch pipes or ports 20 communicating 100 with the ports 2 having the nozzles 4, so that the air passing from the holder through pipe 17 shall eventually escape in a forward direction.

21 indicates a guide frame secured to the 105 upper end of the holder, for the slide valves 22 and 23, the former being adapted to open or close communication between the holder and pipes 12, while valves 23 are adapted to close or open communication between the 110 holder and pipes 17. The valves are provided with similar upwardly projecting rack

bar stems 24 engaging gear pinions 25 mounted on short shafts 26, suitably journaled in frames 27 or equivalent supports. To turn the shafts for the purpose of operating the valves, hand wheels 28 are secured on said shafts, any suitable pawl and ratchet or equivalent mechanism (not shown) being employed to prevent accidental movement of the valves.

- 10 Assuming that the valves 22 and 23 are closed and that valves 10 are open, the engine or its equivalent is started to force air into the holder. As soon as the latter contains sufficient air to insure a uniform and 15 continuous discharge, valves 22 are opened if it is desired to propel the vessel forwardly, as by so doing the air is discharged simultaneously in a rearward direction from all of the nozzles 3. Should a collision be imminent which possibly could be avoided by 20 backing the vessel, valves 22 are closed and valves 23 opened, the result being the air is discharged from the holder through pipes 17 to distributing pipes 18 and thence escapes 25 in a forward direction from nozzles 4, it being understood that if the pressure is sufficient the advance of the vessel is checked almost instantly and a retrograde or backing movement is started.
- 30 In the event that a deflection of the vessel from the direct course laterally in either direction is necessary or advisable, the person in control closes the two valves 22 and 23 at the side toward which it is desired to move 35 the vessel and thus effects the discharge of the compressed air from the nozzles at the opposite side of the vessel only. If it is desired to deflect the vessel from her direct course to a diagonal course to the right valve 40 22 is partly closed to lessen the discharge of air from nozzles 3 at the starboard side of the vessel. If it is desired to deflect the vessel to the left the port valve 22 is partly or wholly closed.
- 45 When the vessel is stationary water will enter the uncovered nozzles and stand in pipes 15 but will of course be forced out by the air when the latter is turned into said pipes. The nozzles 4 are closed by the 50 valves 5 to prevent water entering said nozzles in the ordinary travel of the vessel and if desired, the nozzles 3 may likewise be equipped with corresponding valves, though the necessity of such equipment is not so 55 important, as there will seldom arise the necessity for causing the vessel to move rearwardly any material distance.
- In practice each pipe 9 will be provided with a check-valve (not shown) to retain the 60 air in the holder, but adapted to open under a preponderating pressure from the pump or compressor, the holder being also equipped with a safety valve (not shown) to open if the pressure therein is too high.
- 65 By the employment of a multiplicity of air

discharge nozzles distributed over a large proportion of the water-engaging surface of the vessel, the greater portion of such surface is in contact with air instead of water, and as the former offers less frictional resistance than the latter, the vessel will be propelled at greater speed in proportion to the power developed than can be attained by any vessel having its entire surface below the water line, in engagement with the water.

70

From the above description it will be apparent that I have produced a vessel propelling apparatus possessing the features of advantage enumerated as desirable, and I wish it to be understood that I do not desire to be restricted to the exact details of construction shown and described as obvious modifications will occur to one skilled in the art.

75

Having thus described the invention what I claim as new and desire to secure by Letters-Patent, is:—

80

1. A vessel provided with a plurality of ports in its hull below the level of the water on which the vessel floats, plates secured externally to the vessel near said ports having channels communicating at their opposite ends with said ports and the water sustaining the vessel, certain of said channels communicating with the water sustaining the vessel, at their front ends and the remainder 95 at their rear ends with respect to the prow and stern of the vessel, and means for forcing air through said ports and channels.

90

2. A vessel provided with a plurality of ports in its hull below the level of the water 100 on which the vessel floats, plates secured externally to the vessel near said ports, having channels communicating at their opposite ends with said ports and the water sustaining the vessel, certain of said channels communicating with the water sustaining the vessel, at their front ends and the remainder at their rear ends with respect to the prow and stern of the vessel, a holder for compressed-air, within the vessel, means for charging 110 said holder with compressed-air, and independent valve-controlled means for supplying compressed-air from the holder to the forwardly and rearwardly opening channels.

100

3. A vessel provided with a plurality of 115 ports in its hull below the level of the water on which the vessel floats, plates secured externally to the vessel near said ports having channels communicating at their opposite ends with said ports and the water sustaining the vessel, certain of said channels communicating with the water sustaining the vessel, at their front ends and the remainder at their rear ends with respect to the prow and stern of the vessel, a holder for compressed-air, within the vessel, means for charging said holder with compressed-air, distributing pipes within the vessel and above the water level, pipes extending downward from the distributing pipes, contiguous 120

125

130

to the shell of the vessel, and a plurality of branch-pipes connecting the downward-extending pipes with the said ports.

4. A vessel provided with a plurality of ports in its hull below the level of the water on which the vessel floats, plates secured externally to the vessel near said ports, having channels communicating at their opposite ends with said ports and the water sustaining the vessel, certain of said channels communicating with the water sustaining the vessel, at their front ends and the remainder at their rear ends with respect to the prow and stern of the vessel, spring-valves secured 15 to the said plates for bridging and closing the discharged ends of said channels and adapted to open under the pressure of the compressed-air supplied to said channels through said ports, and means for supplying such compressed-air to said ports and channels.

5. A vessel provided with a large number of ports along its sides below the water level, corresponding nozzles secured externally to the vessel in communication with said ports, 25 certain of them opening rearwardly and the remainder forwardly, a holder for compressed air within the vessel, means for charging said holder with compressed air, distributing pipes above the water level, provided with 30 depending pipes having branch pipes communicating with the rearwardly opening nozzles, distributing pipes having branch pipes communicating with the forwardly opening nozzles, pipes connecting the distributing pipes with the holder, independently 35 of

ently-operative valves for controlling the passage of air from the holder to said distributing pipes, rack bar stems for said valves, shafts suitably journaled and provided with pinions engaging said rack bars 40 and hand wheels for turning said shafts to cause the valves to close or open communication between the holder and the pipes connecting the same with the distributing pipes.

6. A vessel provided with a large number 45 of ports along its sides below the water level, corresponding nozzles secured externally to the vessel in communication with said ports, certain of them opening rearwardly and the remainder forwardly, a holder for compressed 50 air within the vessel, air pumps or compressors, valve-controlled connections between the same and the holder, means for operating the air pumps or compressors, distributing pipes above the water level provided with depending pipes having branch 55 pipes communicating with the rearwardly opening nozzles, distributing pipes having branch pipes communicating with the forwardly-opening nozzles, pipes connecting the distributing pipes with the holder, and independently operative valves for controlling the passage of air from the holder to said distributing pipes.

In testimony whereof I affix my signature, 60 in the presence of two witnesses.

JOHN ELNIEFF.
